UNITED STATES PATENT OFFICE

103,263

DESIGN FOR A SHOE

Sol J. Waxelbaum, Atlanta, Ga.

Application December 28, 1936, Serial No. 66,773

Term of patent 3½ years

To whom it may concern:

Be it known that I, Sol J. Waxelbaum, a citizen of the United States, residing at Atlanta, in the county of Fulton, State of Georgia, have invented a new, original, and ornamental Design for a Shoe, of which the following is a specification, reference being had to the accompanying drawing, forming part thereof, wherein—

Fig. 2 is a side elevational view of the shoe shown in Figure 1.

I claim:

The ornamental design for a shoe substantially as shown.

SOL J. WAXELBAUM.
